INKING MECHANISM FOR PRINTING PRESSES

Harry B. Willett, Sr., Indianapolis, Ind.

Application September 13, 1937, Serial No. 163,534

2 Claims. (Cl. 101—309)

This invention relates to an inking mechanism for a printing press and is particularly adaptable to the type of printing press disclosed in my prior Patent No. 1,993,232, issued March 5, 1935, 5 in which there is provided a stationary type bed and an oscillating platen together with means for feeding a web of paper or other material to be printed across the platen. The present invention, however, is equally applicable to certain 10 other types of presses.

In my prior patent, there is shown a press in which the ink is supplied from a plurality of rotatable discs and is transferred from the discs to the type bed by means of rollers. When the 15 press is used for two color work, each of the discs may be supplied with ink of a different color and a separate type bed is provided beneath each disc in which the copy to be printed in the color carried by that disc is set. The web feed mechanism is set to move the web along the platen in successive steps to bring the printing of the 20 several colors into exact register. In this type of inking construction, the transfer rollers are apt to receive more ink in that portion which engages the central part of the discs. For that reason, 25 printing is not always uniform unless the type bed is much narrower than the width of the disc. This requirement necessitates the type beds being relatively far apart and limits the use of the press to work in which the printed 30 matter occupies a relatively small portion of the sheet to be cut from the web.

One object of the present invention is to overcome this difficulty and to provide an inking 35 mechanism which gives satisfactorily uniform multi-colored printing from type beds set as close together as may be desired. For this purpose, there is employed, instead of the distributing discs just mentioned, a plurality of distributing 40 drums together with a plurality of oscillating rollers cooperating with the drums to distribute the ink uniformly thereon. Transfer rollers take 45 the ink from the drums to the type beds and since both the drums and the rollers are cylindrical, each part of the transfer roller uniformly engages 50 the drum and receives a uniform supply of ink. The drums and oscillating rollers are preferably slightly spaced apart to prevent mixing of the ink 55 of different colors and spacers are provided in the ink fountain trough to prevent mixing of the ink therein. The distributing drums and oscillating rollers are made easily removable and replaceable so that rollers and drums of varying widths to correspond with the particular printing job to be done, may be quickly put in place.

For this purpose also, the partitions in the fountain trough are made adjustable.

Another object of the invention is to provide means for quickly correcting any poor distribution of the ink on the drums. This is accomplished by the provision of independent means for rotating the distributing drums and the oscillating rollers so that the operation of the press as a whole may be stopped and these drums and rollers may continue to operate until the poor 10 distribution has been corrected.

Other objects and features of the invention will be understood from the accompanying drawings and the following description and claims:

Fig. 1 is a side view of a portion of a press to 15 which the invention has been applied. Fig. 2 is a similar side view of the opposite side. Fig. 3 is a rear view thereof. Fig. 4 is a sectional view through the ink distributing drums illustrating the preferred manner of mounting the same for 20 ready interchangeability. Fig. 5 is a sectional view of a detail of the operating mechanism of the oscillating rollers taken substantially on the line 5—5 of Fig. 3.

In the form of the invention illustrated in the 25 drawings, the stationary portions of the press include a pair of side plates 10 and 11. The side plates are suitably secured on a bed plate, not shown, and are secured together in a rigid structure by any suitable means, such as a cross 30 bar 12. A platen 13 is pivotally mounted upon a shaft 14 journaled on the plates 10 and 11 and is provided with a rearward extension 15 between said plates to which there is connected a pitman 16 in turn connected to a crank 17 carried by 35 the main crank shaft 18 of the machine. The crank shaft 18 may carry a flywheel, not shown, as is usual in presses of this type. A motor 19 mounted on a suitable plate 20 may drive the shaft 18 through a sprocket 21, chain 22 and 40 sprocket 23.

Adjacent the upper end of the plates 10 and 11, a fountain trough 24 extends between the same. A fountain roller 25 is carried by a shaft 26 journaled on the plates 10 and 11 and rotates 45 within the fountain trough 24. An adjustable spreader 27 of resilient material engages the roller within the trough to distribute the ink 50 thereon. A ratchet wheel 28 is mounted on the shaft 26 and is engaged by a spring-pressed pawl 29 carried by a lever arm 30 which is freely mounted upon the shaft 26 and is pivotally connected at its opposite end to a collar 31. The collar 31 is freely slidable upon a vertical rod 32, the sliding movement thereof being limited by 55

adjustable stop collars 33 and 34. The rod 32 is pivotally secured at its lower end to a crank 35 carried by a shaft 36 which is journaled in the plates 10 and 11. The shaft 36 is rotated by 5 rotation of the shaft 18 by means of a bevel gear 37 mounted on the shaft 18, a bevel pinion 38 meshing therewith, a shaft 39 to which said pinion is secured, a second bevel pinion 40 secured to said shaft, and a bevel gear 41 meshing 10 with the latter pinion and secured to the shaft 36. The shaft 39 is suitably journaled on the side plate 10. By this means, the fountain roller 25 is rotated step by step in timed relation with the printing operation of the platen 13 and the 15 ink which is deposited in the trough 24 above the spreader 27 is distributed thereon by said spreader. The rate of movement of the fountain roller may be adjusted by adjusting the position of the collars 33 and 34 upon the rod 32.

Above the fountain roller 25, a shaft 42 is pivotally mounted on brackets 43 carried by the plates 10 and 11. Said shaft has secured thereto 20 a pair of lever arms 44 which carry in slotted openings a shaft 45 on which there is mounted a roller 46 which is known as the "duck" roller. The shaft 42 also carries a lever 47 having an opening through which the vertical rod 32 extends. A compression spring 48 surrounds the rod above the lever 47 and abuts against a collar 49 secured to said rod. The lower end of the 25 spring 48 abuts against the lever 47. As the rod 32 is raised, the pressure of the spring 48 is released and the duck roller 46 drops by its own weight into contact with the fountain roller 25 to receive ink therefrom. As the rod 32 is drawn 30 downwardly the spring 48 is pressed against the lever 47 to raise the duck roller 46 into engagement with a set of oscillating rollers 50 which are carried by a shaft 51 journaled in bearings 52 on the plates 10 and 11. The duck roller thus transfers ink from the fountain roller to the oscillating roller at periodical intervals in the operation of the press. In starting the machine or at other 35 times when there is an insufficient supply of ink on the oscillating rollers, the duck roller may be raised and lowered by the manual operation of the lever 47 to transfer a larger supply of ink. The oscillating rollers engage a plurality of drums 40 53 which are secured to a sleeve 54 by means of set screws 55, said sleeve being journaled on a stationary shaft 56 which is secured at its ends to the plates 10 and 11 by means of set screws 57.

Power for rotating the drums 53 and for oscillating the rollers 50 is supplied from a motor 58 45 suitably mounted on a cross member 59 secured to the plates 10 and 11. Said motor rotates a stub shaft 60 by means of gears contained in a housing 61 formed integrally with the motor frame. Said stub shaft is journaled on the plate 60 10 and carries a gear 62 meshing with a gear 63 carried by a shaft 64 which is journaled in the plates 10 and 11. The shaft 64 carries a sprocket 65 about which there is trained a chain 66 which also engages a sprocket 67 secured to the sleeve 65 54. The operation of the motor 58 thus rotates the drums 53.

The shaft 64 also carries a pinion 68 meshing 70 with a pinion 69 carried by a stub shaft 70 mounted on the plate 11. The pinion 69 drives 75 a gear 71 mounted on a shaft 72 journaled in the plates 10 and 11. The shaft 72 also carries an eccentric 73 on which there is freely mounted a circular collar 74 formed as best seen in Fig. 5 and secured in place by a plate 75. A yoke 76 75 embraces the collar 74 and is provided with set

screws 77 having points engaging suitable pits placed diametrically opposite in the outer surface of the collar 74. The yoke 76 is pivoted at its upper end at 78 to a stem 79 which passes through a suitable opening in a lever 80. Said stem is 5 loosely engaged with the lever 80 by means of nuts 81 threaded thereon. The lever 80 is pivotally mounted by means of set screws 82 on a collar 83 carried by a stub shaft 84 which is in turn carried by the plate 11. Said collar is retained 10 in position on the stub shaft by set collars 85. The upper end of the lever 80 is provided with an embossment 86 in which there is reciprocably mounted the lower end of a lever 87. The lever 87 is pivotally mounted by means of set screws 88 15 on a collar 89 freely mounted on the shaft 51. Said collar is retained in position on the shaft by set collars 90.

By means of the linkage just described, the rotation of shaft 72 produces a vertical movement 20 of the yoke 76 which is transmitted to the lever 80 through the stem 79 and causes said lever to oscillate about its pivot screws 82. The oscillation of the lever 80 is transmitted through lever 87 to the collar 89, the embossment 86 providing 25 an extensible connection between said levers. The movement of lever 87 results in horizontal oscillation of the shaft 51 and the oscillating rollers 50 carried thereby.

Ink is transferred from the drums 53 to the bed 30 91 by means of transfer rollers 92. Said rollers are herein shown as four in number, the upper pair being journaled on yokes 93 and the lower pair on yokes 94, there being one of said yokes at each side of the machine. The yokes 93 and 35 94 are pivotally mounted on yokes 95, each of which is in turn pivotally mounted to a stem 96 extending within a tubular housing 97 and having a collar 98 secured on the end thereof. The housings 97 are pivotally mounted at 99 to the 40 plates 10 and 11 and each of said housings is closed by a cap 100 through which the rods 96 extend. Compression springs 101 within said housings abut against the caps 100 and the collars 98. Each of the housings 97 is provided with a rear- 45 ward extension 102 and said extensions are connected by a cross member 103 to which there is attached a pitman 104, the lower end of which is connected to a lever 105 secured to the shaft 36. By means of this construction, the transfer 50 rollers 92 are raised and lowered to transfer ink from the drums 53 to the type bed 91 in timed relation with the printing operation of the platen 13, the spring 101 serving to maintain the proper pressure between the rollers and the type bed and 55 between the rollers and the drums 53.

In multicolor printing with the press just described, each of the drums 53 and its associated oscillating roller 50 may be used for a different color of ink. In that case the trough 24 is divided by spacers 106 into compartments, each of 60 which may receive the ink of the desired color without danger of mixing of colors. The spacers 106 are shaped as best seen in Fig. 2 and are merely hung over the edge of the fountain trough 65 24 at the point or points at which it is desired to divide said trough. The fountain roller 25 and duck roller 46 transfer the inks of different colors to the appropriate oscillating rollers 50, the width of the spacers 106 being sufficient to insure 70 that ink of a given color will not be placed on the wrong oscillating roll. From Fig. 3 it will be apparent that there is considerable space between the oscillating rollers and this space is made sufficiently large to prevent one roller in 75

its horizontal movement from engaging the drum 53 associated with another roller. At the same time, the small space provided between the drums 53 permits a small amount of overtravel of the oscillating rollers and insures a uniform distribution of ink on the drums. Since the drums transfer ink uniformly to the transfer rollers 92 throughout the face of the drums, said transfer rollers may be used with type beds practically as wide as the face of the drums and said type beds may be placed substantially as close together as the drums themselves. This result cannot be obtained by the use of discs instead of drums as in the prior patent previously mentioned. Since the type beds may be close together, the movements of the web of paper necessary to bring the same successively into engagement with each type bed need be only slightly greater than the width of each type bed. Since this movement determines the length of the sheet to be cut from the web at each operation, it is apparent that the sheet need be only slightly longer than the individual width of the type bed. Thus printing of each of the colors may be placed on any part of the sheet.

When it is desired to change the size of type beds, the drums 53 and oscillating rollers 50 may be removed and replaced by drums and rollers of appropriate size for the new printing job. At the same time, the spacers 106 may be moved to divide the fountain trough accordingly. The particular means shown for mounting the drums greatly facilitates their removal and cuts down the make-ready time. In changing drums, the set screws 57 are loosened and the shaft 56 is withdrawn while the drums are suitably supported from above. The drums may then be lowered sufficiently to permit the chain 66 to be disengaged and may then be lifted as a unit. The drums are then removed from the sleeve 54 and others placed thereon, whereupon the new suit may be placed in position. In changing the oscillating rollers 50 it is only necessary to remove bearing caps 107 which hold the shaft 51 in position and then to remove said shaft and

the rollers as a unit. The extensible connection between levers 89 and 87 permits this to be done without disturbing the collar 89.

In starting the press, or whenever a proper distribution of ink has not been secured on the drums 53, the press motor 19 may be stopped while the motor 58 continues to operate until the proper distribution is obtained. At the same time, ink may be supplied by manual operation of the levers 47 and 30.

The foregoing specification describes a preferred form of the invention, the details of which may be varied by those skilled in the art without departing from the scope thereof as defined by the appended claims.

The invention claimed is:

1. In a printing press having an ink receptacle, a fountain roller, means for spreading ink from said receptacle on said fountain roller, a type bed, and a movable platen cooperating with said type bed in the printing operation, the combination of a rotating drum, an oscillator roller engaging said drum, power means for rotating said drum and oscillating said roller in the direction of its axis, means for transferring ink from said receptacle to said oscillator roller, means for transferring ink from said drum to said type bed, and a separate power means operating said platen, rotating said fountain roller and operating said ink transferring means.

2. In a printing press having an ink receptacle, a type bed, a movable platen and power means operating said platen in the printing operation, the combination of a rotating drum, an oscillator roller engaging said drum, means for transferring ink from said receptacle to said oscillator roller, means for transferring ink from said drum to said type bed, and means for rotating said drum and oscillating said roller in the direction of its axis, said last mentioned means being operable independently of the operation of said platen.

HARRY B. WILLETT, Sr.
